(57) **CLAIM**

The ornamental design for a lamp, as shown and described.

DESCRIPTION

FIG. 1 is a front, top, right side perspective view of a lamp showing my new design;

FIG. 2 is a back, bottom, left side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a front, top, right side perspective view of another state of the lamp thereof, with the light sources parts separated;

FIG. 10 is an exploded view of the lamp thereof;

FIG. 11 is an enlarged view of the selected portion 11 in FIG. 1; and,

FIG. 12 is an enlarged view of the selected portion 12 in FIG. 2.

The broken lines shown in the drawings depict portions of the mirror with light that form no part of the claimed design. The additional dot-dash broken lines are for the purpose of showing enlarged areas and form no part of the claimed design.

1 Claim, 12 Drawing Sheets
